Hornitos, Calif.

Application June 9, 1947, Serial No. 139,532

Term of patent 7 years

(Cl. D85—2)

To all whom it may concern:

Be it known that we, Lee Sanchez and Thomas E. Lord, citizens of the United States, both residing at Hornitos, in the county of Mariposa and State of California, have invented a new, original, and ornamental Design for a combined Ash Tray and Cigarette Holder, of which the following is a specification, reference being had to the accompanying drawing, forming a part thereof.

We claim:

The ornamental design for a combined ash tray and cigarette holder, as shown.

LEE SANCHEZ.

THOMAS E. LORD.
